UNITED STATES PATENT OFFICE.

ISAAC M. PEASE, OF CINCINNATI, OHIO.

ARCH SUPPORT.

Application filed August 4, 1922. Serial No. 579,733.

To all whom it may concern:

Be it known that I, ISAAC M. PEASE, a citizen of the United States, residing at Cincinnati, in the county of Hamilton and State of Ohio, have invented a new and useful Arch Support, of which the following is a specification.

The device forming the subject matter of this application is adapted to support the arch of the human foot, and one object of the invention is to improve the support. Another object of the invention is to provide novel means whereby the support may be adjusted longitudinally of the foot of the wearer. Another object of the invention is to provide novel means for assembling the support with the means whereby it is held on the foot.

It is within the province of the disclosure to improve generally and to enhance the utility of devices of that type to which the invention appertains.

With the above and other objects in view, which will appear as the description proceeds, the invention resides in the combination and arrangement of parts and in the details of construction hereinafter described and claimed, it being understood that, within the scope of what is claimed, changes in the precise embodiment of the invention shown can be made without departing from the spirit of the invention.

In the accompanying drawings:—

Figure 1 shows in bottom plan, a device constructed in accordance with the invention; Figure 2 is a section on the line 2—2 of Figure 1; Figure 3 is a section on the line 3—3 of Figure 1; Figure 4 is a detail enlarged from Figure 3; Figure 5 is a longitudinal section showing a modification; Figure 6 is a longitudinal section showing another modification; Figure 7 is a section showing a still further modification.

In carrying out the invention, there is provided a loop-shaped retainer 1, preferably made of elastic material. The ends 2 of the retainer 1 are bridged by a reinforcing strip 3 secured by stitching 4, or otherwise, to the ends of the retainer, to hold the retainer in the loop form shown in the drawings. Eyelets 5 of tubular form are mounted in the strip 3 and in the ends 2 of the retainer 1.

The article includes a support, which

may be in the form of a pad, denoted 55 by the numeral 6 and located within the retainer 1, the pad being of concavo-convex form, as shown in the drawings. The pad 6 comprises a covering including an outer member 7 and an inner member 8, the covering containing a cushion 9 which may be of sponge rubber or any other suitable material. Tabs 10 are attached to the covering at diametrically opposite points and extend beneath the inner member 8 of the covering. A bridge is provided, the same being, if desired, in the form of an arched metallic spring 11, the ends of which are secured at 12 by stitching or otherwise, to the tabs 10. Openings 14 are formed in the 70 bridge or spring 11. Fastening devices 15 are engaged in the openings 14 of the spring or bridge and are engaged with the eyelets 5 in the strip 3 of the retainer 1, the support or pad 6 thus being held releasably and removably on the retainer 1. It is to be understood that the pad 6 may be connected to the retainer 1 in any desired way, but, if preferred, the fastening devices 15 may be in the form of ordinary paper fasteners 80 having their ends bent to engage the reinforcing strip 3 as shown in Figure 1.

Owing to the fact that the retainer 1 is of loop-form and is elastic, the retainer may be shifted longitudinally of the foot of the 85 wearer, and thus the support or pad 6 may be positioned at the desired point depending upon the pathological conditions of the foot.

In the modification shown in Figure 5, parts hereinbefore described have been designated by numerals previously used, with the suffix "a". In this form of the invention, the bridge is in the form of a flexible strip 16 connected at its ends, as shown at 17, at diametrically opposite points of the 95 pad 6^a, the spring 11 of Figure 2 being dispensed with. The cushion 9^a may be made of material which is less elastic than that out of which the cushion 9 is fashioned. The strip or bridge 16 is provided with eyelets 18 adapted to receive fastening devices 19 cooperating with the eyelets 5^a in the strip 3^a to hold the support or carrier 6^a in place on the retainer 1^a.

In Figure 6 of the drawings, parts hereinbefore described have been designated by numerals previously used, with the suffix "b". In this form of the invention, the pad

is dispensed with, the support being in the form of a curved spring 20 having seats 21 provided with openings 22 adapted to receive the fastening devices 23 which are mounted in the eyelets 5^b.

In Figure 7 of the drawings parts hereinbefore described have been designated by numerals previously used, with the suffix "c". In this form of the invention, the support is in the form of a pad 26 connected by fastening devices 25 with eyelets 24 mounted in the reinforcing strips 3^c of the retainer 1^c.

What is claimed is:—

15 1. A device of the class described comprising a loop-shaped band adapted to be adjusted circumferentially of the foot of the wearer, a foot support within the band, and

means for connecting the support with the band for adjustment longitudinally of the 20 foot of the wearer.

2. A device of the class described, constructed as set forth in claim 1, and further characterized by the fact that the support embodies a curved spring strip which promotes resiliency. 25

3. A device of the class described, constructed as set forth in claim 1, and further characterized by the fact that the support embodies a curved spring strip which promotes resiliency and a pad assembled with the ends of the strip. 30

In testimony that I claim the foregoing as my own, I have hereto affixed my signature.

ISAAC M. PEASE.
